MOLDED PLASTIC CONTAINER HAVING HINGED COVER

Filed May 6, 1948

UNITED STATES PATENT OFFICE

2,460,488

MOLDED PLASTIC CONTAINER HAVING
HINGED COVER

Joseph Brunetti, Carlstadt, N. J., assignor to Columbia Protektosite Company, Inc., Carlstadt, N. J., a corporation of New Jersey

Application May 6, 1948, Serial No. 25,452

4 Claims. (Cl. 220—31)

1

This invention relates to portable cosmetic accessory devices and more particularly is directed to improved cover fitted boxes or receptacles of a size to fit into a pocket or handbag for holding face powder, powder puffs or the like.

Among the objects of the invention is to generally improve devices of the character described, which shall comprise few and simple parts that are readily assembled to form a rugged, neat appearing structure having swingable cover closure, which shall be lightweight yet adapted to withstand rough usage, such as frequent opening and closing of said cover closure, which shall be relatively cheap to manufacture, which shall provide a tight powder leakproof box or receptacle that is easily opened and closed, and which shall be practical and efficient to a high degree in use.

Other objects of the invention will in part be obvious and in part hereinafter pointed out.

The invention accordingly consists of features of construction, combination of elements and arrangements of parts which will be exemplified in the construction hereinafter disclosed, the scope of the application of which will be indicated in the claims following.

In the accompanying drawing in which one embodiment of the invention is shown,

Fig. 1 is a cross sectional view taken centrally through a closed pocket or handbag size of powder and puff cosmetic box constructed to embody the invention showing details of the improved cover hinge and snap latching means.

Fig. 2 is a top plan view of the improved cosmetic box shown in Fig. 1 with the cover in side open position.

Figs. 3 and 4 are rear and side elevational views, respectively, of the improved cosmetic box shown in Fig. 1.

Fig. 5 is a fragmentary cross sectional view showing details of the hinge construction taken on line 5—5 in Fig. 1, and

Fig. 6 is a fragmentary cross sectional view similar to Fig. 5 but showing a modified form of the box hinge construction embodying the invention.

Referring in detail to the drawing, 10 denotes a cover fitted receptacle or box, constructed to embody the invention, preferably made of molded material such as desired, colored, opaque or transparent plastic, and when adapted as a cosmetic accessory for holding face powder, powder puffs or the like, is made of a size to readily fit into a pocket or handbag.

Said box 10 may be made with a receiver or

2

holder portion 11 provided with a swingable cover closure 12 which as shown in Fig. 2 is circular shaped. Said cover closure 12 may be relatively shallow with respect to the receiver portion 11 and as shown in Fig. 1 is proportioned to have a depth of about one-half that of the receiver portion. The receiver or holder portion 11 may be formed with a circular flat bottom side 11a which has upstanding therefrom a peripheral wall 11b which terminates in a plane parallel to said bottom side 11a and is provided with a rim, cutback or rabbet 11c. On a front side of receiver 11 midway between said rabbet 11c and the bottom of side wall 11b, an integrally formed protuberance 11d may be provided. Diagonally opposite said protuberance 11d, said wall 11b may have integrally formed therewith an outwardly projecting hinge anchoring box-like structure 11e. The latter may be made hollow as at 11f with parallelly spaced apart walls 11g, having aligned outwardly extending pivoting bosses 11h, positioned a substantial distance from said rib rabbet 11c and said peripheral wall 11b toward the bottom side 11a as seen in Fig. 1.

Cover closure 12 may be formed with an arched top and peripheral flange 12g having a rim rabbet or reverse cut back 12a corresponding to and cooperating with receiver rim rabbet 11c to provide a tight peripheral closure between receiver portion 11 and cover closure 12. Said cover closure 12 may be integrally formed with a snap locking tab extension 12b having a recess 12c positioned to receive and to yieldably interlock with said protuberance 11d, as is clear from Figs. 1 and 4.

Diametrically opposite said tab 12b and integrally formed with said cover closure 12, there is provided a yoke shaped hinge portion 12d formed with an intermediate top cross extension 40 12h and parallelly spaced apart side members 12e positioned to nearly fit against said walls 11g. Said members 12e are provided with aligned openings 12f positioned to receive bosses 11h and forming swingable attachment means for the cover closure 12 on receiver portion 11 as is clear from Figs. 1 to 5. Members 12e are of sufficient peripheral length between the flange 12g of cover portion 12 and opening 12f to provide material capable of a slight stretch so that when recess 50 12c of locking tab 12b is snapped over protuberance 11d the cover closure is clamped in closed position.

Anchoring structure 11e may be made with a cross bracing wall 11j provided in the plane of bottom side 11a as shown in Figs. 1 to 5. The

intermediate top cross extension 12h is formed so as to cover anchoring structure 11e, as is clear from Figs. 1, 3 and 5 and for serving as a stop means for limiting the swing of the cover closure 12 in full open position as shown in Fig. 2.

Fig. 6 shows a modified form of the invention having identical parts, such as receiver portion 111, cover closure 112, yoke shaped hinge portion 112d, openings 112f, cavity 111f and bosses 111h to those in the form in Figs. 1 to 5 except the cross bracing wall 111j which is provided in the plane of the rabbet 11c thus leaving the cavity 111f open at the bottom and closed at the top thereby preventing the face powder from entering the anchoring box 12e.

After constructing the parts of the receptacle 10 as described above the cover closure 12 is hinged to the receiver portion 11 in the assembly by inserting the anchoring structure 11e between the members 12e of the yoke portion 12d. Said members 12e may then be flexed to spread the ends thereof for fitting over the bosses 11h which when released snap in place forming a hinged interconnection for trunnioning the cover closure 12 on receiver portion 11 as is clear from Figs. 2, 3 and 4.

To close the box 10, the cover closure 12 is trunnioned on the hinge construction above described until said rabbets 11c and 12a are inter-fitted and the tab 12b is forced over the protuberance 11d and the latter is seated in the recess 12c.

In assuming this closed position the tab resiliency locks the cover closure 12 to the receiver portion 11 and due to the leverage of yoke members 12e and the position of protuberance 11d said members 12e are placed under tension because of their size, shape and position thereby placing the entire cover closure in clamped position on the receiver portion 11 when the relatively rigid tab 12b is in locked position as is clear from Figs. 1 and 4.

It will thus be seen that there is provided an improved cover fitted receptacle or box whereby the several objects of this invention are achieved and which is well adapted to meet the conditions of practical use.

As various possible embodiments might be made of the above invention, and as various changes might be made in the embodiments above set forth, it is to be understood that all matter herein set forth or shown in the accompanying drawings is to be interpreted as illustrative and not in a limiting sense.

Having thus described my invention, I claim as new and desire to secure by Letters Patent:

1. A portable cosmetic box formed of molded plastic comprising a receiver portion having a flat bottom side and an upstanding peripheral wall terminating in a plane parallel to said bottom side, said peripheral wall provided with a rim cutback rabbet and a protuberance outwardly extending from the exterior thereof, a box-like

hinge anchoring structure integrally formed to extend outward of the exterior of said peripheral wall opposite to said protuberance having oppositely projecting aligned bosses spaced from said wall and said wall rim rabbet, a cover closure fitted to said receptacle portion formed with a rim cutback rabbet shaped and sized to seat on said wall rim rabbet, a tab integrally formed with said cover closure to extend therefrom in an overlying relation with respect to said wall having a recess positioned to receive and yieldably interlock with said protuberance, a yoke shaped hinge portion integrally formed to extend outwardly of the exterior of said cover closure opposite said tab, said yoke portion having parallelly spaced apart members fitted against said box-like structure provided with aligned openings with which said bosses trunnion so constructed and arranged that a slight resilient stretch in said members is provided when the recess of the locking tab is snapped over the protuberance for clamping the cover closure in a closed position on the receiver portion.

2. The cosmetic box as defined in claim 1 in which said bottom side of said receiver portion is circular in shape, said anchoring structure being made hollow with an open end facing the cover closure, said cover closure being of arched cross section having said yoke shaped hinge portion formed with an intermediate top cross extension which completely covers said open end of the hollow anchoring structure.

3. The cosmetic box as defined in claim 1 in which said anchoring structure is made hollow with a cross bracing wall forming an end closure therefor, said yoke shaped hinge portion being formed with an intermediate top cross extension which completely covers said anchoring structure.

4. The cosmetic box as defined in claim 1 in which said bottom side of said receiver portion is circular in shape, said anchoring structure being made hollow with an open end facing said receiver portion bottom side, said cover closure being of arched cross section having said yoke shaped hinge portion formed with an intermediate top cross extension which completely covers said anchoring structure.

JOSEPH BRUNETTI.
